(57) **CLAIM**

I claim the ornamental design for a shelf divider, as shown (as described).

DESCRIPTION

FIG. 1—is a perspective view of the shelf divider;
FIG. 2—is a top view of the shelf divider shown in FIG. 1;
FIG. 3—is a bottom view of the shelf divider shown in FIG. 1;
FIG. 4—is a front view of the shelf divider shown in FIG. 1;
FIG. 5—is a rear view of the shelf divider shown in FIG. 1;
FIG. 6—is a right side view of the shelf divider shown in FIG. 1; and,
FIG. 7—is a left side view of the shelf divider shown in FIG. 1.

The broken lines are for the purpose of illustrating the environment of the design only and form no part of the claimed design.
